UNITED STATES PATENT OFFICE.

OSCAR ZERK, OF CLEVELAND, OHIO, ASSIGNEE, BY MESNE ASSIGNMENTS, TO
GEORGE W. BOWEN, OF AUBURN, NEW YORK.

GREASE-CUP.

1,109,641:

Specification of Letters Patent.

Patented Sept. 1, 1914.

Application filed November 13, 1912. Serial No. 731,206.

To all whom it may concern:

Be it known that I, OSCAR ZERK, a subject of the Emperor of Austria-Hungary, residing at Cleveland, in the county of Cuyahoga and State of Ohio, have invented a certain new and useful Improvement in Grease-Cups, of which the following is a full, clear, and exact description, reference being had to the accompanying drawings.

This invention relates to grease cups of the type wherein there is a cup, a cap screwing onto the cup, a member adapted to restrain the cap against inadvertent rotation, and a spring acting on said member.

The object of the invention is to simplify and cheapen the construction of such a type of grease cup, and render the same more efficient in service and neater in appearance. To this end I provide a cup having a bore, a cap surrounding the cup and screw-threaded thereto, a collar slidably mounted about the cup and having a flange overlapping the cap and having periodic shoulders which cooperate with shoulders on the lower edge of the cap, there being a spring surrounding the cup and acting on the collar to force it against the cap.

The invention is hereinafter more fully explained and its essential characteristics set out in the claims.

In the drawings, Figure 1 is a vertical, central section of my grease cup; Fig. 2 is a horizontal section through the cup and cap just above the collar; Fig. 3 is an enlarged central cross section of the collar, in a plane indicated by the line 3-3 on Fig. 2; Fig. 4 is a detail showing the shoulder carried by the collar, this view being a section on the line indicated by 4-4 on Fig. 2. Figs. 3 and 4 are on an enlarged scale. Fig. 5 is a side elevation of the cap removed.

Referring by numerals to the parts shown in the drawing, 1 represents the cup, 2 the cap screwing thereonto, 3 the collar which coacts with the cap, and 4 the spring for forcing the collar into such engagement. The cup 1 has an externally threaded or nipple portion 10, by which it may be screwed into a suitable opening, and above this an angular portion 11, which may be hexagonal, and above this an enlarged head 12 which has external threads. A suitable bore 13 extends through the head, the angular portion and the nipple portion 10.

The cap 2 is of the approximately cylindrical form shown, having internal threads 20. The cap is shown as provided with a wing 21 on its top by which it may be turned, and with a knurled exterior 22 for the same purpose. The cap has notches 24 in its lower edge which coact with the collar, as hereinafter described.

The collar 3 is a sheet metal member flanged up from a disk in the form shown in Figs. 1 to 4 inclusive. That is to say, there is a disk portion 30 which has a hexagonal opening 31, whereby it may slidably surround the cup without being capable of rotation thereon, and at the outer edge of this disk portion the metal bends downwardly and outwardly, as shown at 32, and then backwardly on itself and then upwardly in the form of a cylindrical flange 33. The diagonal downward and outward flange, provided by the double portion, gives a very neat appearance to the collar, and, at the same time, causes the cylindrical flange to be firmly and stiffly connected with the bottom portion of the collar. The downward flange 32 also makes a retainer for the upper end of the spring as hereinafter explained.

Pressed upwardly from the bottom portion of the collar 3 near the flanges 32 and 33 are a plurality of projections 35, four being shown in the drawings. These projections are inclined gradually on one side and abruptly on the other, as clearly shown in Figs. 2, 3 and 4. The projections are made by pressing upwardly the bottom surface of the collar by suitable dies. The projections are positioned so that they stand adjacent the lower edge of the cap 2 and are adapted to coöperate with such lower edge and with the notches 24 therein. The spring 4 is a conical compression spring. Its lower end rests upon a flange or collar 41 forced into a groove in the member 1 and bearing against a shoulder provided by the angular portion 11 of that member. The upper end of the spring rests against the bottom of the collar 3 within the downwardly projecting flange or doubled edge 32 thereof.

In operation, the cap 2 is turned down, as necessary to force the grease therein through the bore 13. In this operation, as the notches 24 pass off the projections 35, the collar 3 is forced downwardly against the spring action and then springs back when the notches come into registration with the

next projections. The result is that, as the cap is left with collar-projections seating in the notches, the cap is held against inadvertent rotation. The direction of the projections 35 is gradual in the direction in which the cap turns to screw on and abrupt in the opposite direction. The notches of the cap are formed correspondingly to those in the collar, as shown in the case of the two 10 notches illustrated in Fig. 5. From this it results that the cap may be easily turned outwardly on the cup, but a greater resistance is provided against the screwing-off direction. This tends to prevent one turning 15 the cap off when he intends to turn it on; while the cap may be removed whenever required for replacing the grease. It should be noted that the wall 33 of the collar extending over the body of the cap not 20 only increases the neatness of appearance, but prevents dust entering the cup. The projections 35 being simply pressed up from the bottom of the collar, and the collar flange never leaving the wall of the cap, 25 there is no opening for dust to enter.

It will be seen from the drawing and from the above description that my grease cup is very simple in construction. In the embodiment shown it consists of simply five 30 parts; the cup, the cap, the collar, the spring and the washer supporting the spring. These parts are all adapted for economical manufacture and coöperate to produce an efficient and durable grease cup.

35 Having thus described my invention, what I claim is:

1. In a grease cup, the combination of a cup, a cap screwing onto the same, a sheet metal collar slidably mounted on the cup, 40 and a spring forcing the collar toward the cap, the collar being formed with an upwardly projecting annular marginal flange lapping the periphery of the cap, and upwardly extending projections located adjacent the base of the flange and formed by indenting the body of the collar from the under side thereof, the projections coöperating 45 with notches on the lower edge of the cap, substantially as and for the purpose 50 described.

2. In a grease cup, the combination of a cup, a cap screwing on the same, a collar slidably mounted on the cup, and a spring 55 forcing the collar toward the cap, the collar and cap having coöperating projections and

notches, the notches being at the lower edge of the cap and the collar being formed of sheet metal and having its margin bent downwardly and backwardly on itself and upwardly to provide a downward and an upward flange, the upward flange lapping the periphery of the cap, and the collar being indented from the lower side thereof near said flanges forming upward projections constituting the projections coacting with the notches at the lower edge of the cap, substantially as and for the purpose specified.

3. In a grease cup, the combination of a cup having body with shank and an extended head, a cap internally screw threaded screwing onto the head, a collar having bore surrounding the shank of the cup, said collar near its outer edge bent downwardly and then bent backwardly on itself and upwardly to provide for a downward and an upward flange, the upward flange adapted to extend over the outside of the wall of the cap, and a coiled spring surrounding the shank of the cup and having its upper coil 75 lying within the down-turned flange on the collar.

4. In a grease cup, the combination of a cup having a body with an angular exterior and an extended head, a cap internally screw threaded screwing onto the head, a collar having an angular bore surrounding the shank of the cup, said collar being of metal and near its outer edge bent downwardly and then bent backwardly on itself 85 and upwardly to provide for a downward and an upward flange, the upward flange adapted to extend over the outside of the wall of the cap, a spring surrounding the shank of the cup and being of inverted 90 conical form, the upper coil of the spring lying within the downturned flange on the collar, means on the cup for supporting the lower end of the spring, and coöperating shoulders and notches on the bottom portion 95 of the collar and the lower edge of the cap, the shoulders being formed by pressing the bottom portion of the collar upwardly.

In testimony whereof, I hereunto affix my signature in the presence of two witnesses. 100

OSCAR ZERK.
